UNITED STATES PATENT OFFICE.

HENRY COOPER, OF BROOKLYN, AND JAMES P. O'BRIEN, OF NEW YORK,
ASSIGNORS, BY DIRECT AND MESNE ASSIGNMENTS, OF ONE-HALF TO
BERNARD VAN LEER, OF NEW YORK, N. Y.

COIN-OPERATIVE BLOW-TESTING MACHINE.

SPECIFICATION forming part of Letters Patent No. 410,402, dated September 3, 1889.

Application filed April 13, 1888. Serial No. 270,511. (No model.)

To all whom it may concern:

Be it known that we, HENRY COOPER, of Brooklyn, in the county of Kings and State of New York, and JAMES P. O'BRIEN, of the city, county, and State of New York, have invented a new and useful Improvement in Coin-Controlled Blow-Testing Machines, of which the following is a specification.

This invention relates to machinery for receiving and automatically indicating the force of a blow, particularly those which are set for action by and can be operated only on insertion of a coin of certain size or weight. These machines generally comprise a movable padded punching-head on which the blow is struck, a spring or other reacting device acting on the punching-head against the force of the blow, an index adapted to be operated by the punching-head and to indicate the extent of movement of the same and thus the force of the blow, means for temporarily retaining the index at the point to which it is moved, so that it can be observed by the striker and for afterward returning the index to zero and a contrivance whereby the machine is rendered operative on and only on insertion of the proper coin.

The objects of the present invention are to absolutely prevent the movement of the punching-head except when released by the payment of the proper coin; to inform the intending user when and whether the punching-head is locked or released; to secure the immediate return of the punching-head to its normal position and the automatic locking of the same after each blow is struck, while at the same time providing for the temporary locking of the index at the point to which it is moved and preventing it from being thrown beyond that point by its momentum, and to provide for the release of the index and its return to zero a short time afterward, either automatically or by hand, all by simple and efficient means.

The invention consists in various novel combinations of parts and features of construction and arrangement; and in order that the invention may be fully understood we will first describe in detail the mode in which

the invention may be carried into effect, and 50 then point out its various novel features in the claims.

Reference is to be had by letters to the accompanying drawings, forming a part of this specification, in which—

Figure 1 is a vertical section of a coin-controlled blow-testing machine embodying our invention on the line 1 1, Fig. 2. Fig. 2 is a vertical section of the said machine on the line 2 2, Fig. 1. Fig. 3 is a face view of the 60 same. Fig. 4 is a sectional plan view of the same on the line 4 4, Fig. 1. Fig. 5 is a sectional plan view of the same on the line 5 5, Fig. 1. Fig. 6 is a sectional plan of the same on the line 6 6, Fig. 1. Fig. 7 is a detail view 65 of parts of the same, hereinafter referred to.

In the invention thus illustrated an upright case A is mounted on a base appropriate thereto, and the standard A', forming the front of the case, is provided on its face with a circular scale B, the graduations of which are numbered in order to denote pounds. A padded head C, having a tubular shank C', is arranged to project from the front of the case A at a convenient height for the average man to 70 punch or strike, and the shank C' is mounted to slide lengthwise in a fixed tubular guide C², projecting from the back of the standard A' and having a rear head C³, between which and the punching-head C' is interposed a stiff 75 coiled spring C⁴, by which the punching-head C is normally held projected, but which will permit the head C to be forced inward when struck a distance corresponding to the force of the blow. The shank C' is provided with 80 a projecting lug D, which rides in a longitudinal slot formed in the guide C², so as to prevent the shank from turning and to limit its movement in the guide, and the lug D is utilized for the attachment of a cable D', 85 which is carried forward around a stationary pulley D², then upward, and attached to the lower end of a bar E, which is mounted to slide vertically in guides E' on the back of the standard A'. A spring E² is arranged by 90 its reaction to force the bar E normally upward, a stop E³ being provided to limit the movement of the bar E, and the bar E is pro-

vided with a rack E⁴, with which is geared a pinion E⁵, fixed on an arbor, which projects through the standard A' at the center of the scale B, on the face thereof, and carries an index E⁷, which is adapted to turn over and register with the divisions of the scale B. The arrangement is such that the index E⁷ will normally point to zero of the scale; but when the punching-head is struck will, through the action of the sliding shank C' on the cable D' and the sliding bar E, turn the pinion E⁵, and thus the index, until the latter registers with a number of the scale equal to the number of pounds representing the force of the blow. The bar E is provided with a series of ratchet-teeth F, with which a catch F' is held engaged by gravity or a spring, so that when the bar E is thrown downward, as above described, it will be automatically locked by the catch F' in its lower position, and the index E⁷ thus retained at the division to which it was turned. The catch F' is provided with a shoulder F², in connection with which is arranged the pivotal lever G in such a manner that when the lever is swung on its pivot it will strike the shoulder F² and disengage the catch F' from the ratchet-teeth F. The lever G is arranged in the path of a weighted tripper G', suspended from a cable G², which winds on a drum G³, pivoted to the back of the standard A'. Another cable is wound reversely on the drum and sustains a weight G⁴ lighter than the weighted tripper G', and to the drum G³ is attached a fly-wheel H, having a pin H', which is arranged in the path of a pivotal striker H², pivoted to the standard A' and having a sliding connection with the sliding bar E by forking the inner end of said striker and passing it between upper and lower pins S S' respectively, on the bar E, the arrangement being such that owing to the excessive gravity of the weighted tripper G' it will normally overbalance the weight G⁴ and rest on the tripping-lever G, so as to keep the catch F' out of engagement with the bar E; but when the bar E is forced downward, as described, the short arm of the striker H² connected therewith will be thrown upward to strike the pin H' on the fly-wheel H, spin the same in the direction indicated by the arrow a, and thus raise the weighted tripper G'. The tripping-lever G will be thus temporarily relieved of the weight of the tripper G' and will allow the catch F' to dog and lock the bar E, as before stated, until the momentum of the fly-wheel H being exhausted, the weighted tripper G' again falls, (the fly-wheel acting as a speed-check,) strikes the tripping-lever G, and disengages the catch F', so as to permit the bar E to be returned by its actuating-spring E² to its normal upward position. The catch F' is also provided with a cam I, in position to be engaged by one end of the weighted lever I', which is pivoted to the standard A' and carries on its other end a loose pulley I², the arrangement being such that when the lever

I' is swung contra-clockwise on its pivot it also will cause the catch F' to be disengaged from the bar E. Over the loose pulley I² is suspended a cord I³, one end of which sustains a weight I⁴, and the other end a coin-receptacle I⁵ of slightly less weight than the weight I⁴, and from the front of the standard leads a chute J, of a size adapted only to coin of the 75 denomination or character which it is proposed to use, so as to deposit the coin in the receptacle I⁵, so that while the weight of the opposite arm of the lever I' will normally counterbalance that of the cord I³ the weight I⁴, and the receptacle I⁵, so as to keep the lever I' from acting on the cam I of the catch F', when the coin drops into the receptacle I⁵ the additional weight of the coin will cause the lever I' to swing and disengage the catch F', and 80 at the same time cause the receptacle I⁵ to overbalance the weight I⁴ and fall, so as to lift the said weight. The receptacle I⁵ is provided with a movable bottom I⁶, having an arm I⁷, which is adapted to strike a projection K, fixed to the standard A', when the receptacle I⁵ reaches the lower end of its movement, and dump the bottom I⁶, permitting the coin to fall out, the receptacle I⁵ to be again elevated by the weight I⁴, and the lever I' to 95 return to its normal position and leave the catch F' free to engage the bar E. A chute L is arranged to receive the coin falling from the receptacle I⁵ and convey it to a second receptacle M, carried by one end of the lever 100 M', which is pivoted to the standard A', and has a weight M² on its other end, which will normally overbalance the receptacle M, but when the coin is deposited therein will be overbalanced thereby and swung upward. 105 The weighted end M² of the lever M' forms a bolt, which is adapted normally—that is, when the punching-head is projected—to enter between the shoulders of corresponding cross-slots N, formed in the sides of the tubular shank C' of the punching-head C, and also in its tubular guide C², so as to lock the punching-head against movement; but when the lever M' is swung upward, as before described, the bolt will be withdrawn from the 110 cross-slots N, and the punching-head will be thus set free for action. The sliding shank C' is provided with a tripper O, as best shown in Fig. 6, which is arranged to strike, when the shank C' is forced inward, the arm of a 115 lever O², which is connected by a cord O³ with the dumping bottom O⁴, with which the coin-receptacle M is provided, open the said bottom and permit the coin to fall into a final receptacle O⁵ provided therefor, so that when the shank C' is again projected by its reacting spring C⁴ the weight of the bolt M² will tend to cause the bolt to return and lock the shank C' to its guide, as before described.

In the front of the standard A' is provided a window P, back of which is pivoted to swing a carrier P', supporting a double sign P², on one part of which may be printed or produced the words "Wait for signal," or a warn-

ing of similar import, and on the other part the word "Time," or a signal of like meaning; and the carrier P' is connected by a rod or line P² with the locking-lever M', the arrangement being such that when the punching-head C is locked by means of the bolt the above warning—"Wait for signal"—will appear at the window P, but when the lever M' is swung to release the punching-head, as before described, the sign P² will be moved and the above-stated signal—"Time"—be revealed at the window, indicating that the punching-head is ready for action.

In order that the number of times the punching-head is struck may be automatically registered, we arrange a register R and register-operating lever r of common form within the case A, and pass an arm of the lever r between pins r' on the vertically-reciprocating bar E, so that the register will be operated by each reciprocation of the bar E.

To review the operation briefly: The punching-head will be normally locked and the catch F' disengaged from the bar E, but when the coin is dropped into the admission-chute J the punching-head will be released and the signal to strike displayed. When the punching-head is struck, the catch F' will be for a short time allowed to engage the bar E and will retain the same, together with the index, in the position into which they are thrown, while the locking-lever M' will be left free to engage the punching-head shank C'. When the weighted tripper G', returning, again engages the catch F', the bar E will be returned to its normal position, the punching-head having been previously retracted by its spring immediately after being struck and automatically locked by the lever M', so that the machine is automatically reset for operation by the succeeding coin when it may be deposited.

In some instances the case A may be designed in the form of a man with a punching-head C' arranged at or near his stomach and the recording-scale on his chest.

We claim as new and desire to secure by Letters Patent—

1. In a coin-controlled blow-testing machine, the combination, with a tubular guide having a cross-slot, a sliding shank having a punching-head and a cross-slot to register with that in the tubular guide, and shank retracting and indicating devices, as stated, of a balance-lever, a locking-bolt operated thereby to enter the registering slots in the tubular guide and shank, and a coin-receptacle carried by the balance-lever to withdraw the bolt when weighted, substantially as described.

2. In a coin-controlled blow-testing machine, the combination, with a fixed guide and sliding punching-head shank, each hav-

ing a locking-shoulder, of a pivotal balance-lever, one arm of which forms a bolt to engage the locking-shoulders of the guide and shank, and a coin-receptacle carried by the balance-lever, substantially as described. 65

3. In a coin-controlled blow testing machine, the combination, with a punching-head, its guide, and retracting device, of a head-locking device, a balance-lever, and a coin-receptacle supported thereby to release the said locking device, said coin-receptacle having a movable bottom and means for 75 moving said bottom and dumping the coin, substantially as described.

4. In a coin-controlled blow-testing machine, the combination, with a punching-head, its guide, and retracting device, of a 80 head-locking device, a balancing coin-receptacle, and connections to release the said locking device, said coin-receptacle having a movable bottom, and operating-connections between the said movable bottom and the 85 punching-head, substantially as described.

5. In a coin-controlled blow-testing machine, the combination, with a punching-head shank, its guide, and retracting device, of a shank-locking device, a balancing coin- 90 receptacle to operate the said locking device, a tripper carried by the said shank, a movable arm in the path of said tripper, and connections between the said arm and the coin-receptacle, whereby the receptacle is dumped 95 when the shank is retracted, substantially as described.

6. In a blow-testing machine, the combination, with a punching-head, its guide, and retracting device, and an index, an index-operating mechanism connected with the punching-head, of a self-acting index-restraining catch, a catch-tripping device consisting of a fly-wheel and drum revolving together, cables winding reversely on the drum, a weighted 100 catch-tripper on one cable end and a greater or less weight on the other cable end, and a striker operated from the punching-head to spin the fly-wheel, substantially as described. 105

7. In a coin-operative blow-testing machine, 110 the combination of a closed case having a signal-window, a movable double sign, bearing both a warning and a signal, arranged to appear alternately at the window, a punching-head, its retracting-spring, a head-locking bolt, a balancing coin-receptacle in operative connection with the bolt, and a connection between the double sign and the bolt, the whole adjusted and arranged to operate substantially as described. 115
